UNITED STATES PATENT OFFICE

DANIEL J. DE GRASSE, OF NEW YORK, N. Y.

COLLAPSIBLE GOCART

Application filed October 6, 1928. Serial No. 310,761.

This invention relates to a collapsible or folding go-cart and has for an object to provide an improved construction which may be adjusted to act as a vehicle or adjusted to present a collapsed structure having the appearance and shape of a suitcase.

Another object of the invention is to provide a go-cart with a body which, when folded, presents the walls of a suitcase and when unfolded presents a body structure including the different supports found in the usual cart.

A further object, more specifically, is to provide a folding or collapsible go-cart wherein the legs and other supporting members are readily movable to a point within the body so as to be completely closed thereby.

An additional object is to provide a collapsible go-cart wherein certain parts are formed to present a rectangular housing when collapsed and to present a back, bottom and foot-piece when unfolded, the arrangement being such that the wheels and other folding members are within the body when folded and are capable of being moved to an outer operative position when the body is unfolded.

In the accompanying drawings,—

Figure 1 is a perspective view of a collapsible go-cart disclosing an embodiment of the invention, the same being adjusted ready for use;

Figure 2 is an enlarged perspective view of a brace partly shown in Figure 1 and used to brace the wheels when in operative position;

Figure 3 is a perspective view of the go-cart partly folded;

Figure 4 is a perspective view of the go-cart completely folded and locked ready to be carried and transported in any way;

Figure 5 is a longitudinal vertical sectional view through Figure 3 on the line 5—5, with the back in a closed or lowered position;

Figure 6 is a transverse sectional view through Figure 5 on the line 6—6, the parts being shown unfolded.

Referring to the accompanying drawings by numerals, 1 indicates the bottom, 2 the back and 3 the foot-piece of the go-cart when

in a position as shown in Figure 1, these means when folded presenting the walls or body of the enclosing structure, as shown in Figure 4, which is in effect a rectangular box. A strap 4 is secured in place so that the enclosure or box may be carried as a grip, and in order to enhance the appearance of the device so that it will appear as a grip suitable edge trimming or bracing members 5 are provided. These members, in addition to giving a pleasing appearance, act as bracing members for bracing or supporting certain of the parts when folded, and also when unfolded are in an operative position as a go-cart. The bottom 1 is provided with a plurality of strips 6 on which is mounted a plate 7, said plate being of metal or wood or other material, as preferred. Near the rear of the bottom are arranged strips 6' and 8, said strips supporting a plate 9 similar to plate 7, said strip 8 acting as a corner member for bracing that part of the bottom. A front strip 10 is secured to bottom 1 in any desired manner and to this front strip the looped ends 11 of the rails 12 are secured by screws or other suitable means. The rear ends of the bars or rails 12 are secured in any desired manner to the thickened portion 13 of the end wall 14. A pair of guiding or holding rods 15 and 16 are secured to the respective side plates 17, which side plates are connected to the strips 6, as well as to the members 8 and 10. Hook members 18 and 19 coact with bar 16, while identically shaped hook members 19 and 20 coact with rod 15. As all of these hook members and associated parts are identical, the description of one pair of hook members and associated parts will apply to both. As illustrated in Figure 1, hook members 18 and 19 are formed integral with the rods 21 and 22, though they could be made separate and rigidly secured thereto. These rods are positioned to extend downwardly when in use so as to be connected to the plate 23 by rivets, welding, solder or other desired means. The extreme ends of the rods or members 21 and 22 are bent to form axles 24 and 25 for receiving the respective wheels 26 and 27. Each plate 23 is provided with an angle bar 29 having apertures 30 and 31 for receiving the hook members 32.

and 33 extending from the rods 34 and 35. These rods are pivotally connected to the plate 36 through the respective pins 37 and 38 extending through turned-down portions 5 or ears forming part of the plate 36. The plate 36 has a threaded aperture through which the screw 39 extends, said screw being provided with a winged head 40. This screw is adapted to be screwed into the threaded socket 41 (Figure 5) formed in bottom 1 and extending into one of the strips 6. As illustrated in Figure 6, when the screw 39 has been tightened the wheel brace 42 consisting of the rods 34, 35, plate 36 and associated parts act to brace the respective rods 21 and 22 and associated parts, including the wheels 26 and 27. It will be noted that each of the hooks 18 to 20 is formed with a slot so that it may be swung from the position shown at 10 the left in Figure 6 and shown in Figure 1, to the position shown in Figure 3.

Associated with the bottom 1 is the front or foot-piece 3 which is hingedly connected with the bottom 1 by a suitable hinge structure 43, said hinge structure being shown as 15 an ordinary piano hinge. The foot portion 3 is formed with what may be termed a bottom section 44, an end 45 and sides 46 and 47, said ends and sides forming one end 20 of the structure shown in Figure 4 and part 25 of the side edges, while the bottom section 44 coacts with bottom 1 to make one of the side members of the structure shown in Figure 4, the opposite side member being formed 30 by the back 2. Connected with back 2 are 35 side plates 48 and 49 which coact with the side members 46 and 47 for completing the top and bottom members of the structure shown in Figure 4. In order to hold the back 2 unfolded or in an operative position, 40 as shown in Figure 1, elbow braces 50 are provided, and in order to provide a proper grip for manipulating the go-cart, a curved member 51 is secured to back 2, said curved member being out of the way when the parts 45 are folded, as illustrated in Figure 5.

In operation when it is desired to fold the go-cart from the position shown in Figure 1 to the position shown in Figure 4, the screw 50 55 39 is released or unscrewed and then the various hooks 32 and 33 are lifted out of their sockets. The rods 21 and 22 are then swung upwardly so as to be substantially parallel with the bottom 1 and then the parts are slid 60 over the bottom 1 until the wheels and associated parts are nested, as shown in Figure 3. In moving the wheels to this position they are slid beneath the bars 12. End 3 is then turned up to the position shown in Figure 3 and finally the back 2 is lowered after 65 the members 50 have been pushed outwardly from a central point, so that they will swing to a folded position. After the parts have been completely folded, as shown in 70 Figures 4 and 5, the lock or clasp 52 is moved

into locked position and the device is ready to be transported. When in this folded position the device has the appearance of an ordinary suitcase. When it is desired to use the go-cart a reverse action to that just described is carried out and the cart is ready for use. As indicated in Figure 5, there is ample space in one end of the cart for receiving clothing and even a nursing bottle, if desired. 75

What I claim is:—

1. A collapsible go-cart, comprising a foldable body when folded presenting a rectangular enclosure, said body when unfolded forming the bottom of a cart, a back to the cart and a foot-piece to the cart, hinge members for connecting said parts together, a plurality of pairs of wheels, a frame for each pair of wheels, each of said frames having a pair of rods formed with apertured hook-shaped ends, a bar extending through the aperture in each of said ends, said bars being connected to the top surface of said bottom and extending transversely thereof for slidably and swingably connecting said frames with said bottom, said apertured ends being so formed that the frames and wheels may be swung to a position substantially parallel with the bottom and then slid to a position over the bottom when the parts are folded and slid and swung to a position so that the frames will extend at right angles to the bottom when unfolded, and means for locking the frames in an unfolded position. 90

2. A collapsible go-cart, including a frame having a bottom, a pair of rods substantially 100 embedded in the bottom, a pair of frames formed with slotted hooks, said slotted hooks being positioned so that said rods will extend therethrough, traction means carried by each of said frames and a removable brace 105 removably connected with each of said frames and with said bottom, whereby when said brace is functioning the traction means will function and when said means have been removed said frames and traction means are 110 capable of a swinging and sliding movement in such a direction as to be nested on top of said bottom.

3. A collapsible go-cart, including a body, a pair of swinging and sliding frames connected with the body and capable of being slid to a nested position on top of the body and also slid to a position on one side of the body so as to extend at right angles to the plane of the body, and a removable bracing structure for said frames, said bracing structure including a plurality of rods extending through each frame, a central plate and a clamping member for clamping the central plate to the bottom of said body. 115 120 125

4. A collapsible go-cart, including means forming a body, a pair of frames, a pair of wheels connected with each frame, a removable brace for bracing said frames, and a pair of bars extending across said body near 130

each end, each of said frames including a pair of rods having apertured hook ends through which said bars extend, whereby said frames may be swung to a plane substantially parallel to the plane of said body and then slid longitudinally of said bars over said body.

5 Signed at Jamaica, in the county of Queens and State of New York this third day of
10 October, A. D., nineteen hundred and twenty-eight.

DANIEL J. DE GRASSE.
